Attorney.

UNITED STATES PATENT OFFICE.

JOHN A. HEANY, OF YORK, PENNSYLVANIA, ASSIGNOR TO THE TETER-
HEANY DEVELOPING COMPANY, OF CHARLESTON, WEST VIRGINIA, A
CORPORATION OF WEST VIRGINIA.

ELECTRIC SAFETY-FUSE OR CUT-OUT.

SPECIFICATION forming part of Letters Patent No. 758,647, dated May 3, 1904.

Application filed October 12, 1903. Serial No. 176,613. (No model.)

To all whom it may concern:

Be it known that I, JOHN ALLEN HEANY, a citizen of the United States, residing at York, in the county of York and State of Pennsylvania, have invented certain new and useful Improvements in Electric Safety-Fuses or Cut-Outs, of which the following is a specification.

My invention has relation to a safety-fuse or fusible cut-out of the type wherein the fusible material in the form of an easily-melted metallic wire is inclosed in a spool or casing of non-conductive and indestructible material; and in such connection it relates to the construction and arrangement of parts constituting such a safety-fuse or cut-out.

The principal object of my invention is to provide a safety-fuse or cut-out of very simple construction wherein the parts are so assembled that upon the destruction of a fuse-wire the same may be readily and quickly replaced to renew the fuse.

In the carrying out of my invention there is provided a spool of dielectric and indestructible material having a bore extending eccentrically and longitudinally therethrough in which the fuse-wire is adapted to be received, and upon the spool, at each end thereof, is arranged a cap of metal adapted to turn upon the end of the spool, said caps each having a perforation arranged to register with the bore in the spool to permit the entrance or removal of the wire into or out of the spool, said caps being adapted when turned upon the spool to successively cut off the fuse into a required length, shave off the wire to required cross-section or ampere-carrying capacity, bind the wire in the spool, and close the ends of the bore in the spool to inclose the wire within the spool.

The nature and scope of my invention will be more fully understood from the following description, taken in connection with the accompanying drawings, forming part hereof, in which—

Figure 1 is a side elevational view of a safety-fuse or cut-out embodying main features of my invention. Fig. 2 is a longitudinal sectional view of the same, illustrating the

method of inserting the fuse-wire. Figs. 3, 4, and 5 are end elevational views, Fig. 5 being partly in section, illustrating the different positions assumed by the caps during the assembling of the parts together. Figs. 6 and 7 are side elevational and top plan views on a smaller scale, illustrating the invention embodied in a fuse to be placed between two stationary terminals or contacts; and Fig. 8 is a perspective view, also on a smaller scale, illustrating a form of safety-fuse or cut-out embodying the invention, but adapted for insertion in spring contacts or clips.

Referring to Figs. 1 to 5 of the drawings, the fuse or cut-out of cartridge type comprises a spool *a*, having a longitudinal bore *b*, extending eccentrically from end to end for the reception of the fuse-wire *d*. On each end of the spool *a* is arranged to turn a metallic cap *e*, having an opening *e'*, arranged to register with the bore *b* in the spool *a* in one position of the cap, Fig. 3, and when turned to pass said bore *b* to close the same, as illustrated in Fig. 5. On either end of the spool *a*, adjacent to the bore *b*, are arranged one or more semicircular channels *a'* for the reception and retention of an end of the fuse-wire *d*, as illustrated in Fig. 5.

In the operation of assembling the fuse parts the caps *e* are both turned so that their openings *e'* register with and form a continuation of the bore *b*. A strip of wire *d* is then inserted, as illustrated in Figs. 2 and 3. Upon turning each cap *e* the wire *d* is first shaved off and crowded down into the channel *a'* to gage the ampere-carrying capacity of the wire and then cut off by the edge of the opening *e'*, as illustrated in Fig. 4. Upon further turning of the cap *e* the unperforated portion of said cap binds the end of the wire between the spool and the inner metallic face of the cap *e*. To remove the wire, both caps are turned to the position illustrated in Fig. 2 to uncover the ends of the fuse-wire *d* and to permit of said wire being readily withdrawn from the spool *a*.

In Figs. 6 and 7 the cartridge form of fuse or cut-out fits between two stationary contact-

pieces g and g' . In Fig. 8 the caps are enlarged in width, as at e^{10} , so that the fuse may be slipped into spring contact arms or clips, (not shown,) with the broad periphery of the caps 5 e^{10} resting in said spring contact arms or clips.

Having thus described the nature and object of my invention, what I claim as new, and desire to secure by Letters Patent, is—

1. In a safety-fuse or cut-out, a spool of dielectric material having an eccentric, longitudinal bore for the reception of the fuse-wire, combined with metallic caps secured to the spool and free to turn thereon, each cap having an eccentrically-arranged perforation adapted 10 as the cap is turned to register with the bore to open said bore and to close the bore and clamp the fuse-wire to the spool.
- 15

2. In a safety-fuse or cut-out, a spool of dielectric material having an eccentric, longitudinal bore and channels extending from said bore at the ends of the spool, combined with metallic caps turning upon the spool and normally arranged to close the bore and clamp a fuse-wire to said spool, said caps each having an eccentric perforation forming a shearing 20 means to cut off the wire and to crowd said wire into the end channels of the spool. 25

In testimony whereof I have hereunto set my signature in the presence of two subscribing witnesses.

JOHN A. HEANY.
